UNITED STATES PATENT OFFICE.

GEORGE H. JERNBERG, OF BAYONNE, NEW JERSEY.

OIL-ENGINE IGNITER.

1,280,748.

Specification of Letters Patent. Patented Oct. 8, 1918.

Application filed May 3, 1917. Serial No. 166,114.

To all whom it may concern.

Be it known that I, GEORGE HENRY JERNBERG, a citizen of the United States, residing at Bayonne, in the county of Hudson and State of New Jersey, have invented certain new and useful Improvements in Oil-Engine Igniters, of which the following is a full, clear, and exact description, such as will enable others skilled in the art to which it appertains to make and use the same.

This invention relates to improvements in ignition systems and devices for oil engines which may utilize, in normal operation, the heat of compression and localized stored heat of combustion to effect ignition of the oil mixture.

The primary object of the invention is to provide simple, positive and durable means for effecting electric ignition of the combustive mixture in starting and for protecting the electric ignition elements from the effects of high temperature and combustion products in the explosion chamber during normal operation.

Other objects and advantages will be in part noted hereinafter in connection with the description of the accompanying drawing, which illustrates a typical embodiment of the invention, and in which—

Figure 1 is a sectional view of an oil engine cylinder with an improved ignition device applied thereto; and

Fig. 2 is a detail enlarged view of the ignition plug in an adjusted position.

Referring more particularly to the drawing, there is indicated an oil engine cylinder 1 having a piston 2 working therein and having a communicating combustion chamber 3 to which the fuel is injected under pressure.

In normal running, air may be drawn into the engine crank case, where it is compressed and forced into the cylinder, driving out the gases of the previous explosion and leaving the cylinder full of fresh air for the next compression stroke. As the piston nears the end of its stroke, the fuel is forcibly injected into the combustion chamber 3, where ignition takes place from localized heat and moderate compression, that is about 250 pounds. It will be noted that the combustion chamber is entirely outside the cylinder, these parts communicating by a bore 4, and that the fuel is injected only into the 55 chamber, and only at a predetermined point

in the cycle. The wall 5 of the combustion chamber, for the purposes to be described, is also provided with a threaded opening 6 therethrough, into which is screwed a collar or block 7 designed to be fixedly positioned 60 therein and in turn having an internal threaded bore 8. These parts are adapted for tight fit, but there is also preferably provided a gasket 9 wedged between the collar head and the chamber wall exterior to 65 more effectually insure against compression losses.

An electric ignition plug 10, of a length greater than the thickness of the chamber wall, is screwed through the central bore 70 of the collar 7 and is constructed and arranged for relative lengthwise movement, whereby its projection into the chamber may be varied. At its inner end the plug carries an ignition element 11 in the form of 75 an electrical resistance, such as nickel chrome wire, which becomes incandescent when connected with an external battery or other suitable current source. In the exemplary construction illustrated, the ignition 80 element 11 is located in the interior of the plug 10 and is exposed to the combustion mixture within the chamber through one or more side openings 12 in the threaded plug wall.

As indicated, the plug is designed for movement inward and outward with respect to the chamber wall by screwing the same in the collar 7, as by a suitable wrench or other tool. When thus screwed inward to 90 its operating position (Fig. 1) the ignition element 11 is freely exposed to the mixture in the chamber when the fuel is injected. This position of the plug is for starting the engine when cold, and, as will be apparent, 95 it provides an effective method for insuring quick starting and reliable operation until the engine is warmed and the normal means of effecting combustion is thus rendered available. Thereafter, however, if the ignition element remained exposed to the products and heat of combustion within the chamber it would be rapidly attacked thereby and rendered useless. To overcome such objection, therefore, the plug 10 is withdrawn after starting to the position shown 100 in Fig. 2, where the resistance element 11 is completely sealed from the explosive chamber.

It will be noted that the threaded inter- 110

engagement of the plug and collar 7 will provide an interfit between these parts, tending in general to prevent any escape of compression therebetween; but further to insure this result the plug is provided adjacent its outer head with a beveled portion 13 and at its inner end with a seat 14 having a beveled portion 15 which respectively take into and tightly bear against the beveled walls 16 and 17 of recesses in the collar, when the plug is in either extreme position. It is also of advantage to provide the plug about inner end with an unthreaded exterior 18, so that any combustion deposits thereon will not be screwed into the threads of the collar 7 when the plug is withdrawn.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:—

1. In an oil engine, in combination, a cylinder, a combustion chamber communicating therewith, and an electric ignition element constructed and arranged for exposure in said chamber and sealing therefrom.

2. In an oil engine, in combination, a cylinder, a combustion chamber communicating therewith, an electric ignition element constructed and arranged for exposure in said chamber and sealing therefrom during compression and combustion of the fuel mixture therein, and means to insure against compression losses about said element in both positions of the latter.

3. In an oil engine, in combination, means to cause the fuel mixture to attain a pressure and temperature whereby it will spontaneously ignite, and means independent of said first means constructed and arranged for contact with and sealing from the fuel mixture and adapted, in the former relation, to heat the mixture to ignition temperature.

4. In an oil engine, in combination, means to cause the fuel mixture to attain a pressure and temperature whereby it will spontaneously ignite, and electric means independent of said first means constructed and arranged for contact with and sealing from the fuel mixture and adapted, in the former relation, to heat the mixture to ignition temperature.

5. In an oil engine, in combination, a combustion chamber; means including said chamber to effect spontaneous ignition of the fuel mixture during normal operation; and auxiliary means adapted to be positioned in and out of communication with said combustion chamber at will and, in the former relation, to insure ignition of the mixture substantially independently of said first means for starting.

6. In an oil engine, in combination: a combustion chamber; means including said chamber to effect spontaneous ignition of the fuel mixture during normal operation; and an electric element adapted to be positioned in and out of communication with said combustion chamber at will and, in the former relation, to insure ignition of the mixture substantially independently of said first means for starting.

7. In an oil engine, in combination: a combustion chamber; means including said chamber to effect spontaneous ignition of the fuel mixture during normal operation; and an electrical resistance element adapted to be positioned in and out of communication with said combustion chamber at will and, in the former relation, to insure ignition of the mixture substantially independently of said first means for starting, and a current source to effect incandescence of said element.

8. The combination with an oil engine having a combustion chamber and constructed to effect spontaneous ignition of the fuel mixture in said chamber by compression and localized heat of previous combustion; of means for electrically effecting ignition of the mixture at will; said means including a member having an electrical heating element disposed within said combustion chamber, and means for sealing said element from the combustion products and temperatures in said chamber during succeeding combustion by spontaneous ignition.

9. In an oil engine, in combination, a combustion chamber having a threaded opening in one wall, a collar fixedly seated in said opening and provided with a central threaded bore, a plug threaded through said collar and mounted for movement relative to said chamber, said plug having at its inner end an electrical resistance element adapted for incandescence when connected in an electric circuit and said plug and collar being constructed and arranged in a manner whereby said element is movable for exposure within said chamber and sealing within said collar, and means to seal said collar and plug against chamber compression loss therebetween in both relative positions of said element.

10. The herein described method of starting and operating oil engines, which consists in electrically heating the fuel mixture to an

ignition temperature for starting purposes, and thereafter sealing the electrical heating means from the combustion chamber while effecting continued ignition spontaneously by compression of the mixture and stored heat of previous combustion.

11. The method of starting and running oil engines, which includes electrically heating the fuel mixture to ignition temperature when the engine is relatively cold and thereafter protecting the electrical heating means from the products and temperatures of subsequent combustion while effecting continued ignition spontaneously by compression of the mixture and heat of previous combustion.

12. In an oil engine, in combination, a combustion chamber, an electrical ignition means therefor including a plug threaded through a wall of said chamber and having

an ignition element adapted for exposure within said chamber or sealing therefrom by movement of said plug.

13. In an oil engine, in combination, a combustion chamber, and electrical ignition means therefor including a plug threaded through a wall of said chamber and having an ignition element adapted for exposure within said chamber or sealing therefrom at will by movement of said plug, said plug being constructed and arranged to prevent contact of the exposable portion thereof with the threads of said chamber wall when said element is sealed from said chamber.

In testimony whereof I affix my signature, 35 in the presence of two witnesses.

G. H. JERNBERG.
